THREE-LEGGED DOMICAL SHELTER STRUCTURE

John S. Sumner, 728 N. Sawtelle Ave.,
Tucson, Ariz. 85716

Filed Sept. 25, 1972, Ser. No. 291,988

Term of patent 14 years

Int. Cl. D25—03

U.S. Cl. D13—1 D

FIG. 1 is a perspective view of a three-legged domical shelter structure;

FIG. 2 is a side view from the horizon looking through one of the three outside arches;

FIG. 3 is a perspective view looking upwardly from below the base of the three-legged domical shelter structure toward the inner dome structure; and

FIG. 4 is a bottom view of the three-legged domical shelter structure shown in FIG. 1.

I claim:

The ornamental design for the three-legged domical shelter structure, as shown and described.
